ANGLE GAUGE

Filed Sept. 19, 1938

UNITED STATES PATENT OFFICE

2,195,557

ANGLE GAUGE

Fredrick W. Billker and Harry J. Tapper, Milwaukee, Wis., assignors to Milwaukee Saw Trimmer Corporation, Milwaukee, Wis., a corporation of Wisconsin

Application September 19, 1938, Serial No. 230,567

10 Claims.

(Cl. 29—69)

Our present invention relates in general to improvements in attachments for facilitating cutting of various kinds of printer's spacing and blocking stock at any desired angle on an ordinary trimming machine, and relates more specifically to improvements in the construction and operation of angle determining appliances for properly positioning rule, blocks or other spacing material so that the same may be cut or dressed to the desired angle.

The primary object of our invention is to provide an improved angle determining attachment for cutting machines, which is simple and durable in construction, and which is also accurate and flexible in use.

It has heretofore been proposed as shown and described in copending application Serial No. 160,853, filed August 25, 1937, to provide accurately adjustable angle determining mechanism applicable as an attachment to standard cutting and trimming machines, for the purpose of enabling printers to cut rule, blocks and other spacing materials in order to meet the increasing demand for the production of complicated layouts especially in advertising compositions. While this prior mechanism has proven highly satisfactory in actual use, and is quickly attachable to and removable from the cutting machine, it has been found that the range of adjustment which in the prior attachment is from zero to approximately an angle of eighty-five degrees, is not sufficient for all classes of work; and the clamping mechanism for attaching blocks to the angle predetermining arm can not be conveniently utilized to effectively secure blocks and larger pieces of spacing material to the arm. The prior angle gauge moreover is not quite as readily readable and manipulable as might be desired, but is however adapted to perform its intended duty both accurately and satisfactorily in most cases.

It is, therefore, a more specific object of our present invention, to provide various improvements in the details of construction and operation of angle determining mechanisms of the general type disclosed in the above mentioned prior application, whereby the operation is improved and the range of adjustment is increased to nearly the maximum of ninety degrees.

Another specific object of our invention is to provide a new and useful angle gauge in which the work is rigidly held in the desired position during the cutting operation, and which is adapted to cooperate with various sizes or kinds of spacing material.

55 A further specific object of the invention is to

provide an improved telescopic quadrant adjusting device wherein angular adjustments may be made about an imaginary axis without having an obstructive pivot pin at such axis, and in which the work is firmly and accurately supported for all 5 positions of adjustment.

Still another specific object of this invention is to provide a compact and durable angle predetermining attachment for the gauge bar of a standard trimming machine, which can be manufactured and sold at moderate cost and which possesses a wide range of usefulness.

These and other specific objects of the present invention will be apparent from the following detailed description, and some of the novel features 15 of angle gauge attachment, shown but not specifically claimed herein, form the subject of the copending application hereinabove referred to.

A clear conception of the various features constituting the present improvement, and of the 20 construction and operation of an angle gauge embodying our invention, may be had by referring to the drawing accompanying and forming a part of this specification wherein like reference characters designate the same or similar parts in the 25 various views.

Fig. 1 is a plan view of one of the improved angle gauges associated with a fragment of a trimming machine; and showing the angle gauge arm swung at a slight angle, in dot-and-dash 30 lines;

Fig. 2 is a front elevation of the angle gauge attachment alone;

Fig. 3 is an end elevation of the attachment 35 alone;

Fig. 4 is a vertical section through the attachment, taken along the line 4—4 of Fig. 1;

Fig. 5 is an end elevation of the attachment showing a modified clamping jaw assemblage.

While our invention has been illustrated and described herein as being embodied in an angle gauge attachment for a particular type of cutting machine, it is not the intent to thereby unnecessarily limit the scope.

Referring to the drawing, and more especially to Fig. 1, the standard cutting machine shown therein comprises a fixed support or table 5 over the top surface of which various kinds of blocking, spacing and printing material or work is normally slidable while engaging a calibrated gauge bar 6 which is movable along the table and is guided in a groove 7 for movement past a rotary cutter or saw 8. The work may normally be clamped or held manually against the front of 55

the gauge bar 6, and this type of trimming machine is of well known construction.

Our improved angle cutting attachment is shown clamped to the end of the gauge bar 6 nearest the saw 8, in Fig. 1, and is also shown removed from the cutting machine in Figs. 2 and 3, and this attachment comprises in general a quadrant member or frame 9 having a depending rigid lug or leg 10 adapted to coact with the front face of a gauge bar 6; a positioning rod 11 extending away from the leg 10 along the gauge bar 6 and being provided with a positioning pin 12 which is cooperable with the gauge bar end; a clamping block 13 movable by an eccentric 14 which is operable by a handle 15 to clamp the face of the leg 10 against the front face of the gauge bar; a quadrant guide bar 16 slidable in an upper groove 17 in the frame 9 about an imaginary axis 18 and having a lower arcuate slot 19 cooperable with a pin 20 carried by the frame 9 to limit the arcuate movement thereof; an upper calibrated quadrant plate 21 having a lower arcuate groove 22 coacting with the bar 16 and being provided with a stop screw 23 coacting with an arcuate slot 24 formed in the upper portion of the bar 16; a calibrated work engaging bar 25 rigidly secured to and suspended from the quadrant plate 21 by means of upright pins 26; and a clamping member 27 suspended from the frame 9 by means of a horizontal pin 28 and being movable into clamping engagement with the tapered peripheral surface 29 of the quadrant plate 21 by means of a lever 30 having screw thread coaction with the pin 28.

The frame 9 is approximately a quarter segment of an annular ring disposed concentrically of the imaginary axis 18, and the rod 11 is rigidly attached to the leg 10 but may be made adjustable relative to the frame 9, and the attachment 40 may obviously be applied to any portion of the bar 6. The clamping block 13 and eccentric 14 are suspended from a cylindrical column 31 formed integral with and depending from the frame 9 in spaced relation to the leg 10; and the block 13 which embraces the eccentric 14 is prevented from rotating completely therearound, by means of a pin 32 secured to the frame 9 and loosely coacting with a hole in the clamping block. The frame 9 also has an arcuate guide flange 33 secured thereto and cooperating with the guide bar 16 to hold the gauge plate 21 in position, while permitting sliding rotative movement of both the bar 16 and of the plate 21 relative to the frame 9, and to each other, about the imaginary axis 18. The gauge plate 21 is provided with calibrations or graduations 34 representing degrees of displacement; and the slots 19, 24 in the guide bar 16 are approximately forty-five degrees in length so that the gauge plate 21 may be initially swung about the axis 18 approximately forty-five degrees in either direction, without displacing the supporting and guiding bar 16 relative to the frame 9, while continued subsequent swinging of the gauge plate 21 will also move or slide the bar 16 in the groove 17, until the maximum displacement of the plate 21 has been effected. The clamping block or member 27 which is cooperable with the tapered gauge plate surface 29 to hold the plate 21 in adjusted position, is provided with an angle designating line or zero mark 35 which is cooperable with the graduations 34 to predetermine the angle of cutting.

As previously indicated, the auxiliary gauge bar 25 is rigidly secured to the gauge plate 21 by means of the spaced upright pins 26, and the

bar 25 is therefore swingable about the axis 18 when the plate 21 is shifted. The bar 25 has a calibrated strip 36 for determining the length of the piece which is to be trimmed or cut, and also has a T-groove 37 extending throughout the length thereof. Several types of work abutments or clamps may be provided for cooperation with and adjustment along the groove 37. As shown in Figs. 1, 2 and 3, a relatively thin and flat abutment stop 38 which may be clamped in position by means of a lever 39 having a threaded extension 40 piercing the stop 38 and coacting with a clamping block 41 slidable within the groove 37, may be provided. As illustrated in Fig. 1, an alternative form of abutment comprising a rather thick stop 42 with a tapered work engaging face, and clamped in position by means of a lever 43 having a threaded projection 44 coacting with a clamping block 45 slidable within the groove 37, may also be provided. In lieu of the abutment stops 38, 42, an adjustable spring clamp of the type shown in the copending Billker application Serial No. 160,853, may be provided in order to clamp small pieces of work to the bar 25.

While some work may be held manually against the bar 25 and stops 38 or 42, it is desirable in many cases, to clamp the work to the bar. For this purpose, the lower portion of the bar 25 is provided with an elongated reaction plate 46 pivotally attached to the bar by a pin 47 coacting with a slot and located near the imaginary axis 18. This plate 46 is either swingable outwardly beyond the front work engaging face of the bar 25 by means of a spindle 48 journalled in the bar and having an eccentric lower pin 49 coacting with a slot in the plate 46, or may be shifted parallel to its normal inactive position outwardly beyond the face of the bar 25; and the plate 46 also has guide slots coacting with guiding and retaining screws 50 secured to the lower portion of the bar 25, and an end recess coacting with a stop pin to limit its outward movement. As shown in Figs. 1, 2 and 3, the portion of the swingable gauge bar 25 near the axis 18, is provided with a rigid bracket 51 from which a clamping jaw 52 is swingably suspended by means of a pivot pin 53, and the jaw 52 has an integral lug 54 with which an adjustable screw 55 is cooperable to force the clamping jaw against a piece of work resting upon the reaction plate 46 and engaging the front face of the bar 25. A spring 56 secured to the pin 53 serves to urge the jaw 52 upwardly when the screw 55 is retracted. As shown in Fig. 5, the end of the bar 25 nearest the imaginary axis 18 may be provided with a modified clamping jaw 52' which is cooperable with the lower plate 46', and is adjustable by means of a nut 57 coacting with a stud 58. An adjusting member 59 serves to move the jaw 52' outwardly and the plate 46' can also be shifted outwardly as previously described. These work clamping rigs do not interfere with the adjustment of the stops 38, 42 along the swingable bar 25.

During normal use of the improved angle cutting attachment, the frame 9 may be clamped to the main gauge bar 6 of the cutting and trimming machine any desired distance from the plane of cutting, with the aid of the eccentric 14 and clamping block 13, as shown in Fig. 1, and the entire attachment is prevented from extending across the plane of the saw 8 by means of the rod 11 and projection 12, and the leg 10 all of which coact with the gauge bar 6. The attachment is then movable over the table 5 and past the plane of cutting, together with the main

gauge bar 6, and with the auxiliary calibrated bar 25 disposed parallel to the main gauge bar 6, right angle cuts may be made at the ends of work positioned against the front face of the bar 25.

5 When it becomes desirable to position the work at a predetermined angle relative to the plane of cutting, the auxiliary swinging bar 25 may be adjusted so as to cause its front face to assume any desired angle relative to the plane of the 10 saw 8. Such adjustment of the bar 25 can be readily effected by merely manipulating the lever 30 to release the clamping block 27, and by subsequently moving the bar 25 so as to cause the desired graduation 34 to register with the mark 15 35 which is fixed with respect to the frame 9. The bar 25 together with the plate 21 will swing about the imaginary axis 18 when such adjustment is being effected, and during the initial 20 swinging of the gauge bar 25 through an angle of approximately forty-five degrees, the arcuate guide bar 16 does not move with respect to the frame 9. However, as the gauge bar 25 is swung beyond the forty-five degree angle, then the screw 23 coacting with the slot 24 causes the 25 25 arcuate bar 16 to move with the plate 21. The gauge bar 25 may be swung about the imaginary axis 18 approximately eighty-eight degrees from its original position, thereby permitting the work to be trimmed at angles ranging from zero to 30 eighty-eight degrees. This range of trimming is made possible by the swinging of the elements about an imaginary axis 18 and without utilizing a pivot pin near the point of swing, and the telescoping arcuate bar 16 provides an effective support for the gauge plate 21 when the adjustment is carried beyond the forty-five degree position. When the desired adjustment of the gauge bar 25 has been effected, the lever 30 may be manipulated to clamp the gauge plate 21 in adjusted 35 40 position, thus assuring maintenance of the predetermined angle of setting.

The stop 38 is ordinarily sufficient to position the work with reference to the graduated strip 36, but the stop 42 may be utilized to advantage 45 in cutting thin material. If it becomes desirable to clamp the work to the gauge bar 25 either a clamp such as shown in the prior application Serial No. 160,853 may be utilized, or the clamp provided at the pivoted end of the gauge bar 25 50 may be used. The spindle 48 may then be operated to project the lower plate 46 forwardly of the gauge bar 25. The work may then be placed upon the plate 46 and the clamping jaw 52 may be lowered by manipulation of the screw 55, so 55 as to firmly clamp the work between the plate 46 and the jaw 52. The work will then be firmly held in position and need not be held manually, and this clamping attachment has been found extremely useful in connection with the trimming of certain classes of work. The modified 60 clamp of Fig. 5 may also be utilized for this purpose, and when this modified clamp is employed, it is preferable to shift the bar 46 outwardly at all points, and the upper jaw 52' must also be 65 moved outwardly with the aid of the member 59.

From the foregoing detailed description it will be apparent that our present invention provides an improved angle cutting attachment for trimming and cutting machines, which is not only 70 extremely rigid and simple in construction, but which is moreover highly flexible in use. With the improved attachment the vision of the operator is obstructed to the least extent, and angles of from zero to eighty-eight degrees may 75 be readily cut on any kind of work including

blocks and slabs. The improved mounting for the gauge bar 25 and gauge plate 21 insures accuracy in cutting by providing a firm support for the work and by holding the work at the desired angle during the cutting operation, and the 5 attachment may be secured at any distance from the plane of cutting. The improved clamping mechanism comprising the supporting plate 46, 48 and the jaw 52, 52' provides simple and effective means for firmly holding the work in 10 position during cutting, and the entire attachment constitutes a unit which may be readily applied to or removed from a standard cutting and trimming machine. The improved assem- 15 blage has proven highly successful in actual commercial use, and may be manufactured and sold at moderate cost and is also adapted to be operated by a novice.

We claim:

1. An angle gauge attachment comprising, a 20 frame having an arcuate groove therein, an arcuate guide bar slidable within said groove through an angle of approximately forty-five degrees with respect to an imaginary axis, a gauge plate slidable on said frame and having an 25 arcuate groove slidable on said guide bar through an adjoining angle of approximately forty-five degrees, and a work engaging gauge bar swingable about said axis with said gauge plate.

2. An angle gauge attachment comprising, a 30 frame having an arcuate groove therein, an arcuate guide bar slidable within said groove through an angle of approximately forty-five degrees with respect to an imaginary axis, a gauge plate slidable on said frame and having an arcuate 35 groove slidable on said guide bar through an adjoining angle of approximately forty-five degrees, and a work engaging gauge bar swingable about said axis with said gauge plate, said guide bar being fixed relative to said frame during 40 initial angular displacement of said gauge plate and being movable relative to said frame with said gauge plate during subsequent displacement of the latter.

3. An angle gauge attachment for cutting machines, comprising, a frame having an arcuate groove and an arcuate guide flange spaced from said groove, said groove and flange having a common imaginary axis of generation, a guide bar coacting with said groove and being slidable 50 therealong about said axis, a gauge plate slidable cooperable with said flange and guide bar, and a work engaging gauge bar secured to and swingable with said plate about said axis.

4. An angle gauge attachment for cutting machines, comprising, a frame having an arcuate groove and an arcuate guide flange spaced from said groove, said groove and flange having a common imaginary axis of generation, a guide bar coacting with said groove and being slidable 60 therealong about said axis, a gauge plate slidable cooperable with said flange and guide bar, and a work engaging gauge bar secured to and swingable with said plate about said axis, said guide bar being fixed relative to said frame and 65 flange during initial angular displacement of said plate and being subsequently movable with said plate and relative to said frame.

5. An angle gauge attachment for cutting machines, comprising, a frame having an arcuate 70 groove and an arcuate guide flange spaced from said groove, said groove and flange having a common imaginary axis of generation, a guide bar coacting with said groove and being slidable therealong about said axis, a gauge plate slidable 75

- cooperable with said flange and guide bar, a work engaging gauge bar secured to and swingable with said plate about said axis, and releasable means for clamping said work engaging bar relative to said frame in various positions of adjustment.
6. An angle gauge attachment comprising, a frame, a gauge plate swingable upon said frame about an imaginary axis located remote from said frame and plate, a work engaging bar swingable with said plate and having a plane upright work contacting surface approaching said axis, a work supporting plate secured to the lower portion of said bar and being movable from a position of alinement with said plane surface outwardly therebeyond to provide a work supporting ledge, and a clamp movable downwardly toward said ledge near said axis.
7. An angle gauge comprising, a frame movable past a cutter, a gauge plate swingable relative to said frame about an imaginary axis located near the plane of cutting and remote from said frame and plate, a gauge bar swingable with said plate about said axis and having a plane upright work contacting face approaching said axis, a work positioning stop adjustable along said bar, a work supporting plate adjustably associated with the bottom of said bar and being movable outwardly from a position of alinement with said face to provide a work supporting ledge, and a clamp movable downwardly toward said ledge near said axis.
8. An angle gauge comprising, a frame movable past a cutter, a gauge plate swingable relative to said frame about an imaginary axis located near the plane of cutting and remote from said frame and plate, a gauge bar swingable with said plate about said axis and having a plane upright work contacting surface approaching said axis, a work supporting plate secured to the lower portion of said bar and being movable from a position of alinement with said plane surface outwardly therebeyond to provide a work supporting ledge, and a clamp movable downwardly toward said ledge near said axis.
9. An angle gauge comprising, a frame, a gauge plate swingable relative to said frame, a gauge bar swingable with said plate and having a plane upright work engaging surface, a work supporting ledge movable from a position of alinement with said surface forwardly beyond the lower portion thereof, and a work clamping jaw carried by said bar and being adjustable toward said ledge from above said surface.
10. An angle gauge comprising, a frame movable past a cutter, a gauge plate swingably mounted upon said frame and being movable therewith and adjustable relative thereto, a bar swingable with said gauge plate and having an upright work engaging face, a plate adjustably attached to the bottom of said bar and being movable outwardly from a position of alinement with said face to provide a lower work supporting ledge, and a clamp carried by said bar and being movable toward said ledge.
